UNITED STATES PATENT OFFICE.

JOHN H. COES AND FREDERICK L. COES, OF WORCESTER, MASSACHUSETTS.

SCREW-WRENCH.

SPECIFICATION forming part of Letters Patent No. 252,597, dated January 24, 1882.

Application filed December 19, 1881. (No model.)

To all whom it may concern:

Be it known that we, JOHN H. COES and FREDERICK L. COES, both of Worcester, in the county of Worcester and State of Massachusetts, have invented certain new and useful Improvements in Screw-Wrenches; and we declare the following to be a description of our said invention sufficiently full, clear, and exact to enable others skilled in the art to 10 which it appertains to make and use the same, reference being had to the accompanying drawings, which form a part of this specification.

Our invention consists in a peculiarly-constructed handle for wrenches provided with a 15 metal re-enforce or guard about the central portion of the wood and finished flush with the surface thereof, the respective parts being combined as hereinafter more fully described.

In the drawings, Figure 1 represents a side 20 view of a wrench embracing our invention, one-half of the handle being shown in longitudinal section. Fig. 2 is a transverse sectional view at line α α , and Fig. 3 is a side view of the several pieces of which the handle 25 is composed separately shown.

In reference, A denotes the wrench-bar, B the sliding jaw, C the rosette and screw, D the ferrule and step, and A' the bar-shank, all of the ordinary construction as heretofore employed in the well-known "Coes" wrench.

The handle F we construct and arrange in the manner illustrated. It is composed of two pieces or thimbles of wood, F' and F², a central re-enforce or metal ring, I, and the cupped tip-nut K, these several parts being formed and located in relation to each other as shown. The upper thimble or wood piece, F', is provided with a tenon or shoulder, d, to fit the lower end of the ferrule D, and also has its 35 lower end reduced or shouldered at e to fit the re-enforce ring I. The lower thimble or wood piece, F², is provided with similar reductions or shoulders, i and f, at either end, respectively fitting the re-enforce ring I and cupped top of 40 the tip-nut K. The end surfaces, m m', of the wood parts F' F² are squared off to match each other and to fit close when the handle is put together, the united width of the shouldered ends e and i being the same as the width of 45 the ring I. The surfaces m m' can be glued or

cemented when the parts are put together. The ring I can be cast from malleable iron or made from other suitable metal. It is formed to fit tightly over the shouldered ends e and i, and its surface is finished off flush with the surface 55 of the wood portions, so as to leave no projections on the handle. The parts of the handle are slipped over the bar-shank A' in their proper order, as shown, and are clamped together by the tip-nut K, the pressure of which forces the 60 ends of the wood at the respective shoulders firmly against the edges of the metal rings and ferrules and makes a perfectly close fitting joint at each point of contact. The metal re-enforce 65 serves to strengthen the handle and protects it against crushing under heavy weights or castings carelessly dropped onto the wrench. It also prevents the wood from splitting or wearing off flat on the sides.

The woods or thimbles for the handles can 70 be formed from small pieces, or, if preferred, can be made in full lengths and sawed apart to receive the re-enforce ring I. In the latter case the recess for the ring should be formed sufficiently wider than the ring to allow for the 75 saw-kerf.

What we claim as of our invention, and desire to secure by Letters Patent, is—

1. The within-described handle for screw-wrenches, composed of the wood portions F' 80 F², respectively provided with end shoulders, d e i f, and the re-enforce or ring I, surrounding the junction of said wood parts, with its exterior surface finished off flush with the surface of the wood, as hereinbefore set forth. 85

2. The combination, with the wrench-bar shank A' and ferrule D, of the wood thimbles or parts F' F², having end shoulders, d e and i f, and matching surfaces m m', the metal re-enforce ring I, surrounding the center or junction of the wood thimbles and finished flush with the exterior thereof, and the cupped tip-nut K, as hereinbefore shown and described. 90

Witness our hands this 30th day of November, A. D. 1881.

JOHN H. COES.
FREDERICK L. COES.
